ROOFING

George Stanley Logan, Chicago, Ill.

Application October 21, 1933, Serial No. 694,533

2 Claims. (Cl. 108—7)

My invention relates to roofing, and includes among its objects and advantages a simplification of the arrangement of shingles to provide an attractive design.

5 In the accompanying drawing:

Figure 1 is a diagrammatic view of a strip of roofing material illustrating the method of cutting the individual shingles;

Figure 2 is a view illustrating the arrangement 10 of the shingles upon a roof;

Figure 3 is an enlarged view of one of the shingles;

Figure 4 is a sectional detailed view taken along the line 4—4 of Figure 2;

15 Figure 5 is an enlarged view of one corner of the shingle.

In the embodiment selected to illustrate the invention, the shingle comprises a body portion 10 substantially rectangular in cross section having a truncated lower corner 12 and two truncated aligning corners 14. The top corner is cut away at 16 and the two lower sides are slit at 18 just below the corners 14. The lower corner of each shingle is provided with a slit 20.

25 In Figure 1 I have illustrated the method of cutting the individual shingles from a strip 22 of roofing material. The strip is intermittently severed along its median line at 24 to define one lower diagonal edge of each shingle. Similarly, 30 the strip is severed at predetermined spaced intervals along transverse lines 26 to define the other lower vertical edge of each shingle and one of the upper vertical edges of each shingle. The edges of strip 22 itself define the other vertical 35 edge of each shingle.

The arrangement of the lower row of shingles in Figure 1 is the same as the arrangement in the upper row if rotated 180° in the plane of the strip. Thus the truncated corners 12 are arranged in substantially opposed relation angularly across the strip 22 near the middle thereof.

40 In laying the roof, the usual starting strip may be employed to underly the shingles 30 or a row of shingles 28 is fastened to the roof with the aligning edges 14 in abutting relation. The lower part of each shingle 28 is cut off along a transverse line a short distance below the lower ends of the slits 18. A second row 30 is laid in the same way, but with the side edges interlocked 45 into the slits 20. In other words the bridge 21 of each shingle is slipped into the slits 18 of each of two abutting shingles in the underlying row. To increase the effective length of the aligning edges 14 I leave in place a small triangular portion 38 lying beside the slit 18 and extending the 50

edge 14 downwardly. These portions lie outside the rectangular contour of the shingle and one of them is provided from an adjacent shingle, leaving the notch 16 in the other shingle. The other projection is from material lying between the opposed truncated corners 12 in Figure 1. These portions 38 not only prolong the abutment edges but they also enlarge the triangular portions outside the slits 18 but within the contour of the shingle, into squares.

5 In Figure 4, the lip 34 defined by the U-shaped slit 20 is raised slightly to overly the material of the other interlocked shingles. This extra thickness strengthens the interlocking portion of the shingles. The horizontal portion of the slit 15 20 exceeds the horizontal width of the tongues it receives by about one quarter of an inch.

Referring to Figure 2, a nail 36 is driven through each corner of each shingle just above the slit 18 before the next overlying row is placed 20 in position. The bridges below the slits 20 are easily interlocked with the slits 18 by pulling upwardly on the overlying shingle after the bridge 21 has been entered in the lower end of the slit 18. The abutting edges 14 are arranged so that 25 the rows are perfectly aligned when the edges are arranged in contact in the manner illustrated in Figure 2. Thus in each course the truncated portion on the right hand corner of one shingle abuts the truncated portion on the left hand corner of the adjacent shingle. Then each pair 30 of abutting truncated portions is engaged in the U-shaped slot in the lower corner of an overlying shingle, as the next course is secured in place.

35 On reference to Figure 2 it will be noted that the various distances determining the strength of the interlock to resist rupture are closely interrelated. Any upward pull on the overlying shingle, as by wind tending to get under a lower 40 exposed edge, tends to tear the bridge 21 out of the overlying shingle. It also tends to tear the tabs off the underlying shingles. It also tends to lift all three interlocked corners, and this tendency has to be resisted by the adjacent nails 45 36 which grip the underlying shingles only.

To secure sufficient strength against each of these forces without requiring too much overlapping, and still produce the simple shape of exposure required by the customer for esthetic reasons, the relative proportions between the parts should be substantially as in Figure 5, in which the dot and dash lines 39—39 indicate the corner contour of a simple quadrilateral figure. The abutment edge 14 lies substantially one-fourth 50 55

above the dotted horizontal line 40, another quarter below the center line but within the quadrilateral contour, and a lower half outside the contour. The upper end of the slit 18 is substantially level with intersection of the abutment edge 14 and the contour line 39. This makes it possible to get the truncated edge 12, the adjacent diverging side edges of the same shingle, and the adjacent converging side edges of the two shingles in the course below, to meet in two triple intersections at the ends of the edge 12, and still have enough material for adequate strength to resist each of the different straining actions encountered, together with exactly the right over-lap and a reasonable degree of freedom in placing the nails 36 so as to avoid knot holes and the like.

Without further elaboration the foregoing will so fully explain my invention that others may, by applying current knowledge, readily adapt the same for use under various conditions of service.

I claim:

1. A roof made up of diamond-shaped shingles laid in courses with one corner lowermost; each shingle having duplicate truncated side corners, and a locking tab at each side corner extending downwardly outside the contour of the diamond shape, the outer vertical edge of each tab constituting a downward continuation of the adjacent truncated corner; the lower end of each tab having a horizontal lower edge, the inner end of which edge intersects the adjacent side of the diamond; said lower end being separated from the main body of the shingle by an upwardly extending slot beginning at the inner end of the lower end edge of the tab, said slot having its upper end below the level of the horizontal center line of the shingle; the shingles of each course being laid with their truncated side corners and tabs in abutment; each shingle having in its lower corner a single centrally located U-shaped

slot wide enough to receive the abutting tabs of two shingles in the course below, and defining a flexible flap with its free edge lowermost adapted to overlie and thus reenforce both inserted tabs; the lower corner of each shingle being truncated; each end of the truncated lower edge of each shingle intersecting the adjacent diagonal edge at substantially the point where said diagonal edge intersects a diagonal edge of a shingle in the course below.

2. A roof made up of diamond-shaped shingles laid in courses with one course lowermost; each shingle having duplicate truncated side corners, and a locking tab at each side corner extending downwardly outside the contour of the diamond shape, the outer vertical edge of each tab constituting a downward continuation of the adjacent truncated corner; the lower end of each tab being separated from the main body of the shingle by an upwardly extending slot having its upper end below the level of the horizontal center line of the shingle; the shingles of each course being laid with their truncated side corners and tabs in abutment; each shingle having in its lower corner a single centrally located slot wide enough to receive the abutting tabs of two shingles in the course below; the lower corner of each shingle being truncated; each end of the truncated lower edge of each shingle intersecting the adjacent diagonal edge at substantially the point where said diagonal edge intersects a diagonal edge of a shingle in the course below; and driven fastening elements passing through each side corner of each shingle at a point spaced upwardly and toward the vertical center line from the upper end of the adjacent slit, each fastening element also passing through a shingle in the course below near the upper corner thereof.

G. STANLEY LOGAN. 40.
